UNITED STATES PATENT OFFICE.

JOHN BRICKEN, OF CHICAGO, ILLINOIS.

PENCIL.

Application filed January 12, 1920. Serial No. 350,910.

To all whom it may concern:

Be it known that I, JOHN BRICKEN, a citizen of the United States, residing at Chicago, in the county of Cook and State of Illinois, have invented certain new and useful Improvements in Pencils, of which the following is a specification.

My invention relates to improvements in pencils.

10 One object of the invention is to provide a pencil consisting of two tubular telescopic members, the inner member being held in place within the outer member by friction whereby it may be moved longitudinally 15 to cause the lead to project from the opening in the end of the outer member.

Another object is to provide a pencil of this type having a clip which is formed integral with one of said members.

20 In the accompanying drawings in which I have illustrated the preferred embodiment of the invention—

Figure 1 is an elevation of a pencil.

Fig. 2 is a longitudinal section thereof.

25 Fig. 3 is an end view, and

Fig. 4 is a section on the line 4—4 of Fig. 2.

The pencil comprises the telescoping tubular members 1 and 2. The outer member has a tapering end 3 provided preferably with a pair of slots 4, thereby forming jaws having sufficient resiliency to assist in holding the lead in place by friction. The inner member is also provided preferably with 35 a tapering end 5, the end of which is blunt whereby it may engage the rear end of the lead and force it out through the opening. The other end of said inner member is closed preferably by an eraser 6 inserted 40 therein. The eraser may be covered normally by a sheet metal cap 7 having screw threaded engagement with the outer end of said member.

Said inner member is provided preferably with one or more longitudinal slots 8, the diameter of the inner member being such as to permit the same to slide readily within the outer member. To create sufficient friction to maintain the tubular members in any desired position of longitudinal adjustment, the metal adjacent the slot 8 is preferably forced outwardly slightly causing the inner member to bind somewhat when forced into the outer member. 55 Said slot also serves to permit the introduction of small lengths of lead 9 whereby

the inner member may serve as a magazine. A clip 10 is provided and forms an integral part of one of said tubular members preferably the outer one. It consists merely of a 60 projecting tongue which is bent back adjacent to the outer tube about as shown in Fig. 2.

The lead is positioned by slipping it into the opening in the tapering end 3 of the 65 outer tube. It is frictionally held therein between the jaws previously referred to, but may be readily advanced by forcibly sliding the inner tube into the outer tube until the blunt end of the tapering projection 5 engages the rear end of the lead 9. A convenient method of advancing the inner tube is to grasp the cap 7 and impart 70 a rotary motion to said cap and said inner tube, advancing it about in the same manner as if the two tubes had screw threaded 75 engagement with each other.

It will be seen that the construction provided is exceedingly simple, light and inexpensive. The tapering ends are integral 80 with the cylindrical portion of the tubes in each case and the clip being integral with the outer tube, the screw threaded cap is the only additional part required and this is obviously not essential, but may be omitted if desired. By completely withdrawing the inner tube from the outer tube the magazine may be filled with extra lengths of lead or said lengths may be removed from time to time as required in use. 85

90 What I claim is:—

1. A pencil comprising a pair of telescopic members the inner member having an expanded portion adapted to frictionally engage the wall of the outer member, the outer member having an opening at one end to receive a lead, and the end of said inner member abutting against and serving to advance said lead through said opening, said inner member having an opening 100 providing access thereto to form a magazine. 105

2. A pencil comprising telescopic tubular members, each of which is provided with a tapering end, the end of said outer member having an opening and a slot therein, a lead frictionally held within said slotted opening and being abutted by the tapering end of said inner member, said inner member having an expanded portion adapted to 110 frictionally engage said outer member, and a cap on the outer end of said inner mem-

- ber by which said inner member may be grasped.
3. A pencil comprising a pair of telescopic members, one of said members having an expanded portion to provide frictional contact with said other member, the outer member having an apertured tapered end adapted to receive a lead, and a lead adapted to be projected through said aperture upon the sliding of the inner member within said outer member, said inner member having an opening therein providing access thereto to form a magazine.
4. A pencil comprising telescoping members, the outer member having a clip formed integral therewith, the inner member having an opening providing access thereto to form a magazine, said inner member being expanded to frictionally engage said outer member, an eraser secured in the outer end of said inner member, and a screw threaded cap enclosing said eraser.

In testimony whereof, I have subscribed my name.

JOHN BRICKEN.
